UNITED STATES PATENT OFFICE.

HENRY F. BECHMAN, OF BATTLECREEK, MICHIGAN, ASSIGNOR TO THE DUPLEX PRINTING PRESS COMPANY, OF BATTLECREEK, MICHIGAN.

MACHINE FOR MULTICOLOR-PRINTING.

SPECIFICATION forming part of Letters Patent No. 708,013, dated September 2, 1902.

Application filed January 15, 1902. Serial No. 89,886. (No model.)

To all whom it may concern:

Be it known that I, HENRY F. BECHMAN, of Battlecreek, in the county of Calhoun and State of Michigan, have invented certain new and useful Improvements in Machines for Multicolor-Printing; and I hereby declare that the following is a full, clear, and exact description thereof, reference being had to the accompanying drawings, which form part of this specification.

This invention relates to multicolor-printing presses; and its object is to provide a web multicolor perfecting-press in which the web may be perfected in colors in an ordinary one-color perfecting printing mechanism. The invention is an improvement upon the Cox duplex flat-bed reciprocating cylinder web-perfecting presses of the type shown in the patent to Joseph L. Cox, July 5, 1892, No. 478,503, which presses have heretofore been employed for and considered capable only of printing a perfected web in one color; and the particular object of the invention is to enable such a press or others of similar character to produce perfected multicolor impressions upon the web, and this result is accomplished by the novel means hereinafter described, reference being had to the claims for a concise statement of the essential features of the invention.

The accompanying drawings illustrate diagrammatically one of the Cox duplex presses, Figure 1 being a longitudinal diagrammatical section therethrough; Fig. 2, a top plan view of Fig. 1, partly broken to show the web-leads, Fig. 3 being a transverse section on line 3-3, Fig. 1; and Fig. 4 is a detail view of one of the ink-supplies.

In said drawings, *h* *n* designate superimposed type-beds, and *i* *o* the impression-cylinders coöperating therewith. *b* *b* *b* are the infeed-rolls, with which the feed-tapes *B* coact.

s *s* are the outfeed or delivery rolls. *e* *r* are movable web-looping rollers.

a *f*, *g*, *l*, *q*, *u*, *x*, *y*, and *z* are stationary web-guides, and *g* *j* and *p* *m* are movable web-guides at opposite sides of and moving with the respective cylinders.

t is an adjustable web-guide. *v* *w* are angle or web-turning rollers, *F* the "former"

of the folding mechanism, *F*' the guide-roller at top of the former.

H *H* designate ink-fountains at opposite ends of each bed, adapted to supply ink to the inking-rollers *K* *K* at opposite sides of each impression-cylinder.

The foregoing mechanisms are or may be all constructed and adapted to operate as in the well-known Cox duplex combined press and angle-bar folder, the press being constructed substantially as shown and described in Patent No. 478,503, granted to J. L. Cox July 5, 1892. It is therefore unnecessary to give a more detailed explanation thereof. In the ordinary operation of such press the web is led from the roll *a* to and under guide *a*', thence over feed-roll *b*', down under roll *b*², and up over looping-roller *e*, then under guide *f*, to and over guide *g*, then between cylinder *i* and bed *h*, then over guides *j* *k* *l* *m*, then between bed *n* and cylinder *o*, thence over guides *p* *q*, down under looper *r*, up to delivery-rolls *s*, and then over guide *F*' to the former *F*, or the web may be split after passing rolls *s* and one-half thereof led over angle-bars *v* *w* and guide *x* to former *F*. This mechanism produces perfected sheets in one color at each operation, as described in the aforesaid patent, the web receiving one impression from forms on bed *h* and a perfecting impression from forms on bed *n*, but in one color only on each face or side. In order to produce multicolor impressions on the web in such a press, I proceed as follows, in accordance with the present invention: If colors are to be employed, the proper forms are made up, one for each color, as usual in multicolor-printing, and the forms are placed upon the beds, the forms for the same sides or pages of the web being placed on the same beds. For example, the page-forms for printing one side of the web are placed on the lower bed *h* and the page-forms for printing the reverse or perfected side of the web are placed on the upper bed *n*. As indicated in Fig. 3, four forms are placed on bed *h*, forms 10 11 at the left-hand side being "black," form 12 "red," and form 13 "blue." A similar number of forms are placed on the upper bed, forms 14 and 15 being black, form 16

75 80 85 90 95 100

"green," and form 17 "yellow." The colors mentioned are those to be applied to the respective forms. This arrangement will produce perfected papers in five colors—namely, 5 black, red, blue, green, and yellow—and by superimposing these colors other shades may be produced, as well known in multicolor-printing. The different-colored inks are supplied from the same fountain H, the latter 10 being divided by blocks into the desired number of compartments, each containing the desired-color ink. In the example given each lower ink-fountain H would contain compartments for black, red, and blue inks, respectively, 15 while each upper ink-fountain H would contain compartments for black, green, and yellow inks, respectively. The only change in the ordinary Cox duplex press required by this multicolor arrangement is 20 blocking off the fountains and moving the leather feed-tapes B from the drive side to the plain side of the press. A web—say half the usual width—is then placed in the machine and is led from roll a to roller a', over roll b', down under roll b², up over looper e, under guide f, over guide g, under cylinder i, so as to be presented thereby to forms 10 and 11 on bed h, thence up over guide f, back under guide k, over guides l and m, under 25 cylinder o, so as to be presented to forms 14 and 15 on bed n, thence over guides p and q, under looper r, to delivery-rolls s, following thus far the ordinary course of the web through the press and being perfected in black 30 ink—for example, from forms 10 11 and 14 15—the first impression being made in black on the length of web marked 1 in the drawings, the second impression being also made in black on the length of web marked 2 in 35 the drawings. From rolls s the web is led down under adjusting-roller t, thence over guide u, under and over the angle-bars v w, by which it is deflected to one side of its former path, and this portion of the web (indicated at 3) is then carried under guide x, over guide y, back to and over guide u, passing in a direction contrary to length 3, and then may descend to the feed-roll b², as indicated in dotted lines 4' in Fig. 1, and from roll 40 b² it passes up over roller e, and then again through the press, exactly as previously described, back to the roll s, the third impression being made in colors on the length 5 of the web from forms 12 and 13 on bed h and 45 the fourth impression being made on length 6 of the web in colors from forms 16 and 17 on bed n. It will be noticed that length 5 of the web is parallel with length 1 and length 6 of the web is parallel with length 2, as shown 50 in Fig. 2. Impressions are taken simultaneously from all the forms at each operation of the press at four different points in the length of the web. After reaching rolls s the second time the web is led out to guide z, as indicated 55 at 7, and then to the folder or former F.

By arranging the multicolor page-forms and leading the web through the press in the man-

ner described the web can be perfected in colors on the ordinary perfecting duplex flat-bed perfecting-presses without any additional 70 mechanism; but in order to avoid the necessity of laterally moving the feed-tapes on the rolls b b' b² to one side, as above explained, and to avoid the necessity of running printed length of web 4 against the feed-rolls b' b² it 75 is desirable to provide the extra guide-roller D, which is journaled in arms D', attached to the cross-stay D², which latter is a part of the ordinary Cox duplex presses and is located below and in advance of the feed-rolls. The 80 return-lead 4 of the web 3 after passing over roller U is led down under this roller D, as shown in full lines in Fig. 1, and then led back under roller b² up to the looper e, and thence the second time through the press, as 85 described. I thus avoid the necessity of leading the printed web around or against roll b' and also the necessity of laterally moving the feed-tapes on feed-rolls b' b².

It will be observed that the web is passed 90 twice between each printing-couple, being led first through the press between the feed-rolls b b' b² and delivery-rolls s s, and, second, being returned after the first perfected impression to receive another perfected impression 95 in colors, the two lengths of web in the press traveling therethrough alike and being operated together by the same feed and delivery mechanisms, the multicolor effect being produced by using a half-width web, arranging 100 the page-forms and ink-supplies in the novel manner described, and by leading the web through the press in the novel way set forth. When through with color-printing, the pressman has only to clean the fountains and rolls 105 and supply black ink and the ordinary full-width web can be perfected by the press in one color as before. Obviously, if desired, a special press can be made on this principle 110 to print wider webs in colors. 110

Having thus described my invention, what I therefore claim as new, and desire to secure by Letters Patent thereon, is—

1. In a multicolor web-perfected printing-press, the combination of two printing-couples, a plurality of multicolor page-forms arranged in each couple side by side and transversely of the press, a suitable color ink-supply for each form in each printing-couple, means for leading a web successively through both printing-couples over one set of forms therein and taking perfected impressions therefrom; and means for again passing the web successively through both printing-couples over the other set of forms therein and taking perfected impressions therefrom, the impressions from the different page-forms in each printing-couple being superimposed, substantially as described. 115

2. In a multicolor web-perfected printing-press, the combination of two printing-couples, a single feed mechanism, and a single delivery mechanism, a plurality of multicolor page-forms arranged in each printing-couple 120

side by side and transversely of the press, a suitable color ink-supply for each form in each printing-couple; means for leading a web from the feed to the delivery successively through both printing-couples over one set of forms therein and taking perfected impressions therefrom; means for diverting the web to one side, and means for again passing the web from the feed to the delivery through both printing-couples over the other set of forms therein and taking perfected impressions therefrom, and means for directing the web out of the press after it passes the delivery-rolls the second time, substantially as described.

3. In a multicolor perfecting-press, the combination of a pair of printing-couples, a single set of feed-rolls, a single set of delivery-rolls, and guides for directing the web from

the feed-rolls through the printing-couples to the delivery-rolls; with means for diverting the web as it first issues from the delivery-rolls to one side, means for directing the deflected portion of the web around the feed-rolls, back into the press, and leading it again between the printing-couples parallel with its first lead therethrough back to the delivery-rolls, and means for directing the web issuing the second time from the delivery-rolls out of the machine, all substantially as and for the purpose set forth.

In testimony that I claim the foregoing as my own I affix my signature in presence of two witnesses.

HENRY F. BECHMAN.
